(57) **CLAIM**

The ornamental design for an archery accessory bushing, as shown and described.

DESCRIPTION

FIG. 1 is a front-side angled view of an archery accessory bushing, showing the new design.

FIG. 2 is a right-side view thereof.

FIG. 3 is a left-side view thereof.

FIG. 4 is a top view thereof.

FIG. 5 is a bottom view thereof.

FIG. 6 is a front view thereof.

FIG. 7 is a back view thereof; and,

FIG. 8 shows an archery accessory bushing in an archery bow.

The broken lines in FIGS. 1-7 depict unclaimed portions of the design. The broken lines in FIG. 8 depict environmental structure and unclaimed portions of the archery accessory bushing. All broken lines are for illustrative purposes only and form no part of the claimed design.

1 Claim, 8 Drawing Sheets
